A. V. Comings,
Inventor

By *Clarence A. O'Brien*

Attorney

UNITED STATES PATENT OFFICE.

ANTIONETTE V. COMINGS, OF EAST GRAND FORKS, MINNESOTA.

BOBBED-HAIR CURLER.

Application filed June 16, 1924. Serial No. 720,368.

To all whom it may concern:

Be it known that I, ANTIONETTE V. COMINGS, a citizen of the United States, residing at East Grand Forks, in the county 5 of Polk and State of Minnesota, have invented certain new and useful Improvements in a Bobbed-Hair Curler, of which the following is a specification.

This invention relates to new and useful 10 improvements in hair curlers and has for its principal object to provide a simple and efficient device which may be readily and easily operated for receiving a lock of hair which is adapted to be rolled therearound, 15 means being further provided for preventing the counter-rotation of the roll of hair on the curler.

A further object of the invention is to provide a hair curler of the above mentioned 20 character, which is principally adapted to be used in conjunction with the curling of bobbed hair and includes a device which will be positive and efficient in its use.

A further object of the invention is to 25 provide a hair curler of the above mentioned character, which is simple in construction, inexpensive, strong and durable and furthermore adapted for the purposes for which it is designated.

Other objects and advantages of this 30 invention will become apparent during the course of the following description.

In the accompanying drawing forming a 35 part of this specification and in which like numerals designate like parts throughout the same:

Figure 1 is a top plan view of my improved device.

Figure 2 is a side elevation.

Figure 3 is a similar view showing the 40 same in an open position for receiving a lock of hair, and

Figure 4 is a sectional view taken approximately on line 4—4 of Figure 2.

In the drawing wherein for the purpose 45 of illustration is shown the preferred embodiment of my invention, the numeral 1 designates generally my improved hair curler, and the same comprises an elongated 50 strip of spring metal, the same being bent intermediate its ends to provide a loop 2. The arms 3 and 4 respectively formed by bending the strip of spring metal are adapted to contact with each other for substantially 55 ly their entire length and the arm 4 is of greater length than the arm 3 and has its

free end provided with a substantially V-shaped member 5, the purpose of which will hereinafter be more fully described.

The free end of the arm 3 is adapted to 60 be normally disposed below the inwardly extending portion 6 formed on the extreme free end of the arm 4 in the manner clearly shown in Figures 1 and 2 of the drawing and a locking means is provided thereby 65 whereby the arms are held in contacting relation. The arms are further provided with interfitting means and the same comprises a longitudinally extending channel 7 formed in the inner face of the arm 4 and the 70 longitudinally extending rib 8 formed on the adjacent face of the arm 3. This construction is clearly illustrated in Figure 4 of the drawing. The purpose of this arrangement is to provide a means for preventing 75 any transverse movement of the arms with respect to each other when the same are in locked engagement and a lock of hair is secured between the inner adjacent faces of the arms. For facilitating the disengagement of the free end of the arm 3 from the free end 6 of the arm 4 whereby the arms may be separated for inserting or removing a lock of hair from the curler, the protuberance 9 is struck up from the 80 arm 3 adjacent the free end thereof in the manner clearly illustrated in Figures 2 and 3 of the drawing.

Disposed in the loop 2 of the curler is an elastic ring or band 10. The purpose of this 90 member is to prevent the counter rotation of the hair curler in the manner hereinafter to be more fully described.

The use of my improved hair curler may be briefly stated as follows: With the parts 95 arranged as shown in Figure 3 of the drawing, a lock of hair is inserted between the arms 3 and 4 and the free end of the arm 3 is then disposed below the free end 6 of the arm 4 and held in locked engagement there- 100 with thereby clamping the lock of hair securely between the contacting arm. The hair curler is then rotated whereby the hair between the arms will be rolled around the same until the desired length of hair has 105 been wound. The elastic band or ring 10 is then placed around the roll of hair on the hair curler and engages the substantially V-shaped portion 5 formed adjacent the free end of the arm 4 whereby the counter rotation 110 of the hair curler with the hair rolled around the same will be prevented. The

manner in which the band 10 extends around the sides of the hair curler and fits in the V-shaped notch 5 is clearly shown in the dotted lines in Figure 1 of the drawing.

5 It will thus be seen from the foregoing description, that a hair curler for use in connection with the curling of bobbed hair has been provided which is simple in construction, inexpensive, and the parts further so 10 arranged as to enable the same to be readily and easily actuated for securing or removing a lock of hair from engagement therewith. The provision of the protuberance 9 will furthermore enable a person to more easily and 15 readily disengage the free end of one arm for engagement with the other.

20 While I have shown the preferred embodiment of my invention, it is to be understood that various changes in the size, shape and arrangement of parts may be resorted to without departing from the spirit of the invention and the scope of the appended 25 claims.

Having thus described the invention, what 25 I claim is:—

30 1. A hair curler comprising a strip of spring metal bent intermediate its ends to provide a loop, and a pair of arms, one arm being of greater length than the other, the free end of the longer arm being bent inwardly to provide a means for engaging the free end of the other arm, said arms being adapted to contact with each other for substantially the length thereof and receiving a 35 lock of hair therebetween; an elastic band supported in said loop, the longer arm being provided with a notch adjacent the free end thereof for receiving the opposite end of the elastic band after the lock of hair has been 40 rolled around the arm to prevent the counter rotation of the same.

45 2. A hair curler comprising a strip of spring metal bent intermediate its ends to provide a loop, and a pair of arms, one arm being of greater length than the other, an elastic band disposed in said loop, said arms being adapted to contact with each other for substantially the entire length, the free end

50 of the longer arm being disposed inwardly to receive the free end of the other arm whereby the same are held in locked engagement, the longer arm being provided with a substantially V-shaped notch adjacent the free end thereof, said elastic band being 55 adapted to extend around the side of the arm and the roll of hair wound around the arm and engaging said V-shaped notch to prevent the counter rotation of the arm, and means for facilitating the separating of the free end of said arm from engagement with each 60 other.

3. A hair curler comprising a strip of spring metal bent intermediate its ends to provide a loop, and a pair of arms, one arm being of greater length than the other, an elastic band disposed in said loop, said arms being adapted to contact with each other for substantially the entire length, the free end of the longer arm being disposed inwardly to receive the free end of the other arm whereby the same are held in locked engagement, the longer arm being provided with a substantially V-shaped notch adjacent the free end thereof, said elastic band being 65 adapted to extend around the side of the arm and the roll of hair wound around the arm and engaging said V-shaped notch to prevent the counter rotation of the arm, means for facilitating the separating of the free end of said arm from engagement with each 70 other, said arms being so formed as to prevent the transverse movement of the same with respect to each other.

75 4. An article of the class described comprising a hair curler having a pair of arms, means for detachably interengaging the ends of said arms, said means consisting of a loop on one of said arms under which the other arm engages, a recess in said loop and an elastic band secured in the end of the arm opposite to the loop and adapted to be stretched over both of said arms and engage 80 with said recess.

90 In testimony whereof I affix my signature.

ANTIONETTE V. COMINGS.
